VACUUM PUMP

Kenneth C. D. Hickman, Rochester, N. Y., assignor to Distillation Products, Inc., Rochester, N. Y., a corporation of Delaware

Application May 11, 1945, Serial No. 593,129

7 Claims. (Cl. 230—101)

1

This invention relates to improved multi-stage jet vacuum pumps of the fractionating type.

Fractionating multi-stage jet vacuum pumps are known in the prior art; see, for instance, Hickman 2,080,421, May 18, 1937, Hickman 2,153,189, April 4, 1939, and Hickman and Kuipers United States patent application 443,732, filed May 20, 1942 (now Patent 2,379,436, July 3, 1945). Such pumps are provided with a plurality of boiler compartments connected to different jet nozzles and are adapted to use an organic fluid, and during operation to fractionate the organic liquid in the different boilers and arrange the components so that the low vapor pressure components exert their pumping action toward the low pressure side of the pump and the high vapor pressure components toward the high pressure side of the pump. I have noticed that the level of the liquid in the different boilers of such pumps as well as of multi-stage multi-boiler pumps in general is subject to great variation during operation. Thus, the boiler compartments are under different pressures and the liquid may, therefore, surge from one boiler into another resulting in an over supply of liquid in some boilers while other boiler compartments may have too little liquid, or may even boil dry. Obviously this has an undesirable effect on the pumping action.

This invention has for its object to overcome the foregoing difficulties. Another object is to provide improved multi-boiler, jet vacuum pumps in which the liquid is maintained during operation at an approximately uniform or constant level. Another object is to prevent surging of liquid during operation of multi-stage jet vacuum pumps. A further object is to improve the operation of multi-jet vacuum pumps. A still further object is to improve the state of the art. Other objects will appear hereinafter.

These and other objects are accomplished by my invention which includes a multi-stage jet vacuum pump provided with a plurality of boilers and with means for controlling the supply of working liquid to the boilers whereby surging and/or unsatisfactory distribution of the liquid is avoided.

In the following description I have illustrated several of the preferred embodiments of my invention but it is to be understood that these are set forth for the purpose of illustration and not in limitation thereof.

In the accompanying drawings wherein like numbers refer to like parts, I have illustrated several embodiments of my invention wherein:

Fig. 1 is a vertical section of a multi-stage jet vacuum pump of the condensation type provided with means for maintaining a uniform level of liquid in each of the boiler compartments;

Fig. 2 is a fragmentary enlargement of the pump shown in Fig. 1 illustrating the construc-

2

tion of the means for maintaining a uniform level;

Fig. 3 is a fragmentary vertical section of a modification of the apparatus illustrated in Fig. 1 and

Fig. 4 is a vertical section of a multi-stage jet vacuum pump operating on the principle of an ejector and provided with means for maintaining a uniform level in the individual boilers.

Fig. 5 is a vertical section of a multi-stage ejector pump provided with adjustable means for controlling the level and supply of pump fluid.

Referring to Figs. 1 and 2, numeral 10 designates a cylindrical casing provided with an integral base plate 12 and a flange 14 adapted to be connected in a gas-tight manner to the system to be evacuated (not shown). Numerals 16, 18 and 20 designate concentric cylinders which rest upon the base plate 12 at the lower extremity, and which are provided with caps 22, 24 and 26 respectively which cooperate therewith to form jet nozzles 28, 30 and 32 respectively. Numeral 34 designates openings through which vapors pass into the throat of jet nozzles 28, 20 and 32. Cylinder 16 is provided at the base with an outwardly flared portion 36 and a collar 38 which serves to make contact with the inside wall of casing 10 and space the cylinders 16, 18 and 20 in a position concentric therewith. Collar 38 is provided with a plurality of openings 40 for liquid to flow from the upper walls of 10 into boiler 42 by way of openings 44 in the lower edge of cylinder 16. Numeral 45 designates an electrical heating unit mounted upon the base plate 12. Referring especially to Fig. 2, numeral 46 designates a float which is integral with arm 48 which is hinged at 50. To the float is attached a curved arm 52 which passes through a valve opening 54 which is closed or opened by valve seat 56 actuated by the float 46. Numeral 58 designates a similar float which actuates valve 60 and serves to open or close valve opening 62. Numeral 64 designates a cylindrical reservoir which is connected to the space between cylinders 10 and 16 by conduit 66. The upper portion of reservoir 64 is formed into a narrow cylindrical chimney 68 which protrudes into high-pressure arm 70 of the pump and is concentric therewith so as to form an ejector pump in cooperation with the walls of 70. Numeral 72 designates a pump fluid which assumes the approximate level shown when the pump is operated but which fills the reservoir to approximately the level indicated by the dotted line 74 when the pump is not in operation.

Referring to Fig. 3, numeral 80 designates an annular gutter mounted upon the inside wall of casing 10. Numeral 82 designates a conduit connecting the gutter 80 with the lower part of reservoir 64. Gutter 80 serves to collect liquid and deliver it to reservoir 64 where it is boiled and

fractionated and then the boiled liquid delivered to the boiler compartment 42 by way of conduit 66.

Referring to Fig. 4 numeral 90 designates an ejector diffuser tube having a circular cross section provided with jet nozzles 92, 94 and 96. Numeral 98 designates a flange mounted upon the intake end of the ejector pump which is adapted to be connected to the system to be evacuated (not shown). Numeral 100 designates a conduit connected to the high-pressure end of the diffuser tube which leads to the atmosphere or to a backing pump (not shown).

Numerals 102, 104 and 106 designate boilers connected respectively to jet nozzles 92, 94 and 96 by conduits 110, 112 and 114 respectively. Numeral 116 designates a float which actuates valve 118 of boiler 102 and numeral 120 designates a float which actuates valve 122 of boiler 104. Numeral 124 designates a conduit conveying liquid collecting in the high-pressure end of the diffuser tube to the intake of pump 126. Numeral 128 designates a conduit conveying liquid from the exhaust pump 126 to the boiler 106. Numeral 107 designates heaters for the boilers.

Referring to Fig. 5 numerals 140, 142 and 144 designate a plurality of ejector pumps connected in series, the low pressure end 146 of pump 140 being connected to the system to be evacuated, (not shown) and the high pressure end 148 of pump 144 being connected by conduit 150 to a fore pump (not shown). The high pressure end of pump 140 is connected to the low pressure, or intake end of pump 142 by conduit 152 and the high pressure end of pump 142 is connected to the intake, or low pressure, end of pump 144 by conduit 154.

Pumps 140, 142 and 144 are actuated by vapors delivered respectively to jet nozzles 156, 158 and 160. Pump fluid issuing from these nozzles entrains gases and forces them into the high pressure end of each of the pumps in known manner. The pump fluid is condensed on the air cooled walls of the diffuser tubes of each of the pumps and flows by gravity into the high pressure ends of each of the pumps. The pump fluid then drains from each of the pumps into conduit 162, pumps 142 and 144 being provided with liquid traps 164 and 166, respectively, which prevent passage of gases backwards into the previous pump in the series. Numeral 168 designates a gear pump which forces the working fluid flowing from the high pressure ends of each of the pumps through heat exchange coil 170 and thence into boiler 172, which is heated by heater 174 and which supplies actuating vapors to jet nozzle 160 by way of conduit 176.

Numerals 178 designates an overflow conduit which is slideably mounted in gas-tight, packed gland 180, overflow liquid contained therein being forced by pump 182 through heat exchange coil 184 and thence through conduit 186 into boiler 188, which is heated by heater 190 and which supplies working vapor to jet nozzle 158 by way of conduit 192. Numeral 194 designates a slideably mounted overflow conduit which delivers liquid to the intake side of pump 196, which forces this liquid through conduit 198 and into boiler 200. Boiler 200 is provided with a heater 202 and supplies working fluid to the jet nozzle 156 by way of conduit 204. Numeral 206 designates a conduit connecting boiler 200 to an auxiliary boiler or purifier 208 which is provided with heater 210. The upper part of purifier 208

is connected to the upper part of boiler 200 by conduit 212.

In operating the apparatus illustrated in Figs. 1 and 2, flange 14 is connected to the system to be evacuated and the backing pump is connected to the high-pressure side 70 in the usual manner and heating element 45 is put into operation. The mixed organic liquid 42 which may be a petroleum fraction, a diphthalic acid ester, etc., 10 is thus vaporized and the vapors rise through vertical concentric tubes 18 and 20. Vapors pass through openings 34 and issue as high velocity jets through nozzles 28, 30 and 32. Gases diffusing from the system to be evacuated are entrained in these high velocity jets and are forced 15 downward into the high-pressure side arm 70. Reservoir 72 is likewise heated and the high velocity stream of vapors passes upward through 68 and entrains the gases from the lower portion 20 of the pump casing 10 and forces them upwards into the high-pressure arm 70. The spent pump fluid is condensed on the walls of 70 and 10 and flows downward through opening 40 in collar 38 and thence through opening 44 into boiler 42. 25 Some of this liquid also flows through conduit 66 into boiler 72, where there is continual purification by vaporization with return of the useful components by condensation in the side arm 70. The liquid in the base of the pump flows in 30 sequence from one concentric cylinder into the other. Thus, the liquid in the boiler 42 flows through valve 54 into the next boiler compartment. The liquid then flows through valve 62 into the center boiler compartment. As the 35 liquid passes from one boiler compartment to the other it is fractionated and the lighter portion is distilled off and issues as vapor through the working jet of that particular boiler.

Valves 54 and 62 effectively control the level 40 of the liquid in the boilers and if properly positioned will maintain the level uniform in each of the boilers. As the liquid in one boiler becomes depleted the float valve will sink, opening the valve and permitting additional liquid to 45 flow therein. The height of the floats can be varied so that the level of liquid in the boilers will be the same or different, depending on the conditions desired. The level of the liquid in each boiler is thus maintained constant whereas, 50 in previous constructions it varied considerably, as explained above.

The operation of the modification shown in Fig. 3 is much the same as above described. However, gutter 80 collects all of the spent pump 55 fluid and delivers it into reservoir 64 where it is first partially fractionated and is then returned to the boilers of the pump by way of conduit 66.

In operating the apparatus of Fig. 4, flange 98 is connected to the system to be evacuated and 60 conduit 100 is connected to the atmosphere or to a backing pump, as the case may be. Reservoirs 102, 104 and 106 are filled with a suitable pump fluid, preferably a petroleum fraction, which should be of higher vapor pressure than that used 65 in Fig. 1, as is explained in the above-mentioned Hickman and Kulpers application. Boilers 102, 104 and 106 are then heated by burners 107 to cause vaporization of the liquid contained therein. The vapors issue from jets 92, 94 and 96 as 70 high velocity streams. Gases from the system to be evacuated are pulled into the low pressure end of diffuser tube 90 and are forced by the action of the high velocity jets into conduit 100. The spent jet vapors are condensed on the walls of 90 by 75 the cooling action of air, although water cooling,

etc., may be used, if desired, and this liquid condensate is withdrawn by pump 126 through conduit 124 and forced into boiler 106. As the level of liquid in boiler 104 is lowered float valve 122 is opened to permit additional liquid to flow therein. The same action takes place in boiler 102.

In operating the apparatus illustrated in Fig. 5, the low pressure end 146 of pump 140 is connected to the system to be evacuated (not shown) and conduit 150 of pump 144 is connected to the fore pump (not shown), which is put into operation. Heaters 174, 190, 202 and 210 are put into operation. Pumps 168, 182 and 196 are actuated. Pump fluid in boiler 172 is vaporized and the vapors pass upwardly through conduit 176 and issue as a high velocity stream from jet nozzle 160. Gases in conduit 154 are entrained in this stream and are forced into the high pressure end 148 of the pump. The pump fluid vapors are condensed on the diffuser walls and flow by gravity through trap 166 and into conduit 162. Vapors from boiler 188 pass upwardly through conduit 192 and issue as a high velocity stream from jet nozzle 158. Gases in conduit 152 are entrained in this stream and are forced into conduit 154 and thence into pump 144, as previously described. Spent pump fluid from pump 142 drains by gravity into trap 164 and flows into conduit 162. Similarly, vapors generated in boiler 200 issue as a pumping stream from jet nozzle 156 and entrain gases from the system to be evacuated and force them into conduit 152. Spent pump fluid is condensed and flows by gravity into conduit 162.

The condensed and cooled pump fluid in conduit 162 is forced by pump 168 through heat exchange coil 170 where heat contained in liquid flowing through conduit 184 is picked up and used to preheat the liquid in coil 170. This pre-heated liquid then flows into boiler 172. Overflow pipe 178 is adjusted to maintain the desired constant level of liquid in boiler 172. Liquid overflowing is forced by pump 182 through heat exchange coil 184 and thence into boiler 188. The more volatile constituents in the pump fluid have been removed in boiler 172 and the intermediate vapor pressure constituents are volatilized in boiler 188 and are used in jet nozzle 158. Overflow conduit 194 is adjusted to maintain the desired level in 188. Liquid overflowing is forced by pump 196 into boiler 200 where the lowest vapor pressure constituents are vaporized and are used in jet nozzle 156. Pumps 182 and 196 not only serve to transfer liquid from one boiler to another, as described, but also prevent passage of liquid in a reverse direction, which might otherwise take place with variations in pressure.

Pump fluids usually contain or generate non-volatilizable or heavy products and these are segregated and retained in purifier 208. Thus, the liquid in 200 flows through conduit 206 into conduit 208, where it is heated by heater 210. Vapors thus generated pass through conduit 212 into boiler 200. Non-volatilized matter remains and collects in purifier 208.

While my invention is of particular value in connection with fractionating condensation pumps where the boilers segregate the different components and are preferably heated to progressively higher temperatures as the low pressure end of the pump is approached, it is also useful with multi-boiler multi-stage jet pumps in general, which are actuated with vapors of organic fluids. Thus a multi boiler jet pump could be supplied with a single component working fluid and the working fluid would be controlled and

supplied to the various boilers as described. With such a pump it would improve the pumping action in many cases to use a lower temperature in the boiler supplying vapors to the lowest pressure jet and higher temperatures in the boilers supplying the jets working against higher pressures.

What I claim is:

1. A multi-jet vacuum pump adapted to employ an organic liquid and in operation to fractionate the organic liquid by flowing it in sequence through a plurality of boilers arranged to distribute the components of the liquid in such manner that the low vapor pressure components exert their pumping action toward a low pressure pumping zone of the pump and the high vapor pressure components exert their pumping action toward a high pressure pumping zone of the pump, the normal flow of said organic liquid through said boilers being from a higher pressure pumping zone to a lower pressure pumping zone, said pump including a plurality of boilers, liquid passageways interconnecting said boilers in series, and flow-controlling means associated with at least one of said boilers and comprising valve means adapted and arranged to open and close a liquid passageway from said boiler, a float in said boiler, and a connecting member secured respectively to said float and said valve means and constructed and arranged to close said valve means upon upward movement of said float and to open said valve means upon downward movement of said float in response to changes in the liquid level in said boiler.
2. A multi-jet vacuum pump adapted to employ an organic liquid and in operation to fractionate the organic liquid by flowing it in sequence through a plurality of boilers arranged to distribute the components of the liquid in such manner that the low vapor pressure components exert their pumping action toward a low pressure pumping zone of the pump and the high vapor pressure components exert their pumping action toward a high pressure pumping zone of the pump, the normal flow of said organic liquid through said boilers being from a higher pressure pumping zone to a lower pressure pumping zone, said pump including a plurality of boilers, liquid passageways interconnecting said boilers in series, a valve in at least one of said liquid passageways interconnecting a boiler in a higher pressure pumping zone with a boiler in a lower pressure pumping zone, said valve being adapted and arranged to move from a position permitting flow of liquid through said passageway to a closed position, an actuating float disposed in one of said boilers interconnected by said passageway, a rigid connecting arm secured respectively to said float and said valve and constructed and arranged to close said valve upon upward movement of said float and to open said valve upon downward movement of said float in response to changes in the liquid level in said boiler, and guide means for said float limiting lateral movement thereof.
3. A multi-jet vacuum pump adapted to employ an organic liquid and in operation to fractionate the organic liquid by flowing it in sequence through a plurality of boilers arranged to distribute the components of the liquid in such manner that the low vapor pressure components exert their pumping action toward a low pressure pumping zone of the pump and the high vapor pressure components exert their pumping action toward a high pressure pumping zone of the pump, the normal flow of said organic liquid

through said boilers being from a higher pressure pumping zone to a lower pressure pumping zone, said pump including a plurality of boilers, liquid passageways interconnecting said boilers in series, a valve in at least one of said liquid passageways interconnecting a boiler in a higher pressure pumping zone with a boiler in a lower pressure pumping zone, said valve being adapted and arranged to move from a position permitting flow of liquid through said passageway to a closed position, an actuating float disposed in said boiler in said lower pressure pumping zone, a rigid arm connecting said float and said valve constructed and arranged to open said valve upon downward movement of said float and to close said valve upon upward movement of said float in response to changes in the liquid level in said boiler, and guide means for said float limiting lateral movement thereof.

4. A multi-jet vacuum pump adapted to employ an organic liquid and in operation to fractionate the organic liquid by flowing it in sequence through a plurality of boilers arranged to distribute the components of the liquid in such manner that the low vapor pressure components exert their pumping action toward a low pressure pumping zone of the pump and the high vapor pressure components exert their pumping action toward a high pressure pumping zone of the pump, the normal flow of said organic liquid through said boilers being from a higher pressure pumping zone to a lower pressure pumping zone, said pump including at least three boilers, liquid passageways interconnecting said boilers in series, flow-controlling means associated with at least one said boiler which is positioned between a boiler in a higher pressure pumping zone and a boiler in a lower pressure pumping zone and interconnected with said other boilers by said liquid passageways, said flow-controlling means comprising a valve positioned in one of said liquid passageways from said first-named boiler and movable from a closed position to an open position, an actuating float positioned in said first-named boiler, a rigid arm connecting said valve and said float constructed and arranged to move said valve toward said closed position upon upward movement of said float and toward said open position upon downward movement of said float in response to changes in the liquid level in said boiler, and guide means for said float limiting lateral movement thereof.

5. A multi-jet vacuum pump adapted to employ an organic liquid and in operation to fractionate the organic liquid by flowing it in sequence through a plurality of boilers arranged to distribute the components of the liquid in such manner that the low vapor pressure components exert their pumping action toward a low pressure pumping zone of the pump and the high vapor pressure components exert their pumping action toward a high pressure pumping zone of the pump, the normal flow of said organic liquid through said boilers being from a higher pressure pumping zone to a lower pressure pumping zone, said pump including at least three boilers, liquid passageways interconnecting said boilers in series, flow-controlling means associated with at least one said boiler which is positioned between a boiler in a higher pressure pumping zone and a boiler in a lower pressure pumping zone, said flow-controlling means comprising a valve in the liquid passageway connecting said first-named boiler with said boiler in said higher pressure

5 pumping zone, an actuating float disposed in said first-named boiler, a rigid arm connecting said float and said valve constructed and arranged to close said valve upon upward movement of said float and to open said valve upon downward movement of said float in response to changes in the liquid level in said boiler, and guide means for said float limiting lateral movement thereof and comprising a rigid guide arm secured to said float and pivotally secured to a wall of said boiler above said liquid passageway.

6. A multi-jet vacuum pump adapted to employ an organic liquid and in operation to fractionate the organic liquid by flowing it in sequence through a plurality of boilers arranged to distribute the components of the liquid in such manner that the low vapor pressure components exert their pumping action toward a low pressure pumping zone of the pump and the high vapor pressure components exert their pumping action toward a high pressure pumping zone of the pump, the normal flow of said organic liquid through said boilers being from a higher pressure pumping zone to a lower pressure pumping zone, 15 said pump including at least three boilers, liquid passageways interconnecting said boilers in series, flow-controlling means associated respectively with at least the boiler in the lowest pressure pumping zone and the boiler in the next higher pressure pumping zone the respective flow-controlling means for each said boiler comprising a valve in the liquid passageway connecting said boiler with the next higher pressure pumping zone, a float disposed in said boiler, a rigid arm 20 connecting said float and said valve arranged and constructed to close said valve upon upward movement of said float and to open said valve upon downward movement of said float in response to changes in the liquid level in said boiler, 25 and a guide arm rigidly secured at one end to said float and pivotally secured at the other end to a side wall of the boiler.

7. In a multi-jet fractionating diffusion vacuum pump of the type adapted to employ an organic pumping liquid, a plurality of boilers, liquid passageways connecting said boilers in series and opening into each said boiler in a zone thereof lower than the normal level of pumping liquid in said boiler, surge-controlling means for at least one of said boilers constructed and arranged to prevent objectionable surging of pumping liquid throughout said boilers, said surge-controlling means comprising a valve in one said passageway opening into said boiler and movable from a closed position to an open position, a liquid actuated float disposed in said boiler, a rigid arm connecting said valve and said float, said arm being of sufficient length to maintain said valve in the open position when the liquid level in said boiler is normal, and a guide arm secured at one end to said float and pivotally secured to a wall of said boiler to limit lateral movement of said float while permitting vertical movement thereof in response to changes in the liquid level in said boiler.

KENNETH C. D. HICKMAN.
